UNITED STATES PATENT OFFICE

2,509,330

VEHICLE BODY AND FENDER STRAIGHTENING APPARATUS

Frank W. Bowie and Edward N. Sturdevant,
Binghamton, N. Y.

Application June 18, 1948, Serial No. 33,688

8 Claims. (Cl. 153—32)

1

This invention relates to an apparatus for use on the sheet metal parts of motor vehicles, such as the top and mud guards, for straightening dents and other distortions occurring due to accidents.

Numerous types of devices and mechanisms have been employed for straightening out sheet metal portions of motor vehicles. For many years, this work was performed purely through the use of hand tools, rollers, etc., and this method was not found to be particularly satisfactory. An apparatus in common use at the present time for performing the functions referred to is illustrated and described in the F. J. Hauschild Patent No. 2,148,943. In such patent, a yoke possessing a reasonable degree of resiliency is provided with means at one end thereof for supporting a dolly in contact with the side of the work opposite that at which pressure is to be exerted, and such pressure is applied through the medium of a ram reciprocated by a suitable air motor to be impacted against the work supported by the dolly. A bell or plate surrounds the ram and is held in firm engagement with the work as supported by the dolly, and the only resilience involved in the clamping of the work is provided through the yoke which connects the dolly to the ram-operating air motor. Mechanisms of this character have been found reasonably satisfactory in operation, constituting a substantial improvement over the prior manual methods of performing the work, but it is difficult to secure a perfect smoothing of the rough or dented surface due to the inadequacy of the cushioning action with which the apparatus is held in position relative to the work.

An important object of the present invention is to provide an improvement over the structure shown in the Hauschild patent referred to wherein the work is more effectively cushioned with respect to the elements between which it is clamped, thus providing for a smoother operation of the apparatus and the accomplishing of more efficient results.

A further object is to provide such an apparatus wherein the work is clamped between a suitable dolly and an ironing ring in which the ram is operable, and to so mount the ironing ring relative to the air motor as to provide an improved cushioning action and to permit part of the smoothing work to be effectively performed by the ironing plate.

A further object is to provide novel means for utilizing air pressure rather than a mechanical clamping means for fixing the position

2

of the air motor relative to the work, thus rendering wholly feasible the use of an ironing plate in conjunction with the ram and increasing the facility with which the apparatus may be used as well as improving the results obtained.

A further object is to provide an apparatus of this character wherein the air motor has associated therewith a cylinder carrying an ironing plate surrounding the ram, the cylinder being so mounted as to be freely longitudinally movable for adjusting the apparatus relative to the work, the cylinder being urged toward the work by air pressure during the use of the apparatus to hold it in position relative to the work while cushioning its movement instead of fixing it positively in an adjusted operative position.

Other objects and advantages in the invention will become apparent during the course of the following description.

20 In the drawings we have shown one embodiment of the invention. In this showing:

Figure 1 is an end elevation of the apparatus.

Figure 2 is a side elevation of the same.

25 Figure 3 is an enlarged detail perspective view of the ram and ironing plate, the parts being shown separated.

Figure 4 is an enlarged axial sectional view through the power head of the apparatus, parts being broken away and parts being shown in elevation.

30 Figure 5 is a detail sectional view on line 5—5 of Figure 4, with the air motor piston raised from the position shown in Figure 4.

Figure 6 is a transverse sectional view on line 35 6—6 of Figure 4; and

Figure 7 is a detail perspective view of the motor cylinder.

Referring to Figures 1 and 2, the numeral 10 designates a tubular yoke of the general type disclosed in the Hauschild patent referred to above, this yoke possessing a small degree of resiliency. A suitable fitting 11 at one end of the yoke supports a dolly 12, which may be of any desired type according to the work being performed. It will be obvious that the dolly is purely conventional and any desired form of such element may be employed.

The opposite end of the yoke fits within a sleeve 14 of a cylindrical tool holder 15 having 50 its axis arranged in alignment with the axis of the other end of the yoke 10. The yoke is fixed in the sleeve by tightening a suitable wing nut 16 or any other desired type of fastening means.

Referring to Figure 4, it will be noted that the cylindrical tool holder 15 has an internal annular

flange 18 at its lower end forming a cylindrical bearing in a manner to be described. Between the upper and lower ends of the tool holder 15, an internal annular flange 19 is formed integral with the tool holder, and the two purposes of this flange also will be described below. At its upper end, a cap 20 is threaded into the tool holder and is provided with a suitable fitting 21 for connecting the cap 20 to a hose 22 leading to a suitable source of compressed air controlled in the usual manner by a hand or foot valve (not shown). The cap 20 is provided with a cylindrical depending extension 24 of substantial length as viewed in Figure 4 and having an air passage 25 extending entirely therethrough for the flow of air under pressure from the hose 22.

A cylinder 28 is mounted to slide axially in the flanges 18 and 19, these flanges serving as bearings for the cylinder 28. Adjacent its upper end, the cylinder 28 is provided with an external flange 29 adapted to engage the top of the flange 19 to limit downward movement of the cylinder 28. The flange 19 thus functions both as a bearing for the cylinder 28 and as means for limiting downward movement of such cylinder. From the flange 29 to its lower extremity, the cylinder 28 is of uniform external diameter except as referred to below, and accordingly it will be apparent that the cylinder 28 is insertable into the tool holder 15 from the upper end thereof prior to the application of the cap 20.

A cap 32 is threaded in the upper end of the cylinder 28 and is provided with an external flange 33 seating upon the top end of the cylinder 28. The lower end of the axial extension 24 projects into the cap 32 and is sealed relative to the cap by a suitable sealing ring 34.

The cap 32 is provided with a depending cylinder 36 having a bottom wall 37 defining the lower limit of a cylindrical chamber 38 therein. This chamber receives the lower end of the axial projection 24 upon upward movement of the cylinder 28, and it will become apparent that such upward movement of the cylinder may be accomplished by hand when the chamber 38 is not connected to the source of air pressure.

The cylindrical portion 36 of the cap 32 is provided with radial openings 40 communicating with an external annular groove 41 turned in the cylinder 36. This groove, when the parts are assembled as in Figure 4, is in direct registration with an internal annular groove 42 formed within the upper end portion of the cylinder 28. The groove 42, in turn, communicates with one or more longitudinally extending passages 43 drilled in the wall of the cylinder 28 and communicating at its lower end with an internal annular groove 44 formed in the inner wall of the cylinder 28 at a point spaced substantially below the wall 37.

A piston 48 is mounted to reciprocate in the cylinder 28 and is provided with an axial bore 49 in its upper end communicating with radial passages 50 (Figures 4 and 5). As will become apparent, the passages 50, when the piston 48 is adjacent its upper limit of movement, communicate with the annular groove 44 for the flow of compressed air therefrom into the upper end of the cylinder 28 beneath the wall 37. When the piston 48 is at its lower limit of movement as shown in Figure 4, the groove 44 communicates with radial passages 52. These passages communicate with the upper ends of longitudinal passages 53 and these passages extend downwardly through the length of the piston 48

to communicate with the bottom of the cylinder 28 beneath the piston 48 to urge the latter upwardly.

The tool holder 15 obviously is provided between the flanges 18 and 19 with a chamber 56, and this chamber communicates with the interior of the cylinder 18 above the piston 48 through one or more radial passages 57. These passages are open to the cylinder 28 above the piston 48 when the latter is at its lower limit of movement, but are covered by the piston as the latter moves upwardly. The chamber 56 may communicate with the atmosphere through an exhaust port 58 drilled through the tool holder 15, or it may communicate with the atmosphere through passages 59 formed by milling flat surfaces 60 on the outer surface of the cylinder 28 as shown in Figures 4 and 7. In the latter figure it will be noted that two of the exhaust ports 57 have been shown, and such ports have been found ample for the exhausting of air pressure from above the piston 48. Similar exhaust ports 61 are drilled through the cylinder 28 to exhaust the bottom of the cylinder 28 beneath the piston 48 when the latter moves upwardly.

The lower end of the cylinder 28 is axially recessed as at 65 to receive an upwardly extending cylindrical sleeve 66 externally flanged at its lower end as at 67 to be secured to an ironing plate 68. This plate is shown in the present instance, for example in Figure 3, as being circular in form and as having a depending circular rounded flange 69 on the bottom face thereof. A snap ring 70 is arranged in a groove 71 formed in the external surface of the cylinder 28 adjacent the lower end thereof, and a round-ended pin 72 is carried by the snap ring and engageable in an annular groove 73 formed in the outer surface of the sleeve 66. The round end of the pin 72 serves to frictionally hold the sleeve 66 in position while permitting its ready removal and insertion by the proper application of endwise forces to the sleeve 66.

A ram 75 is reciprocable in the sleeve 66 and is provided with an external flange 76 received in an internal groove 77 formed in the sleeve 66. The length of the groove 77 is substantially greater than the width of the flange 76 to permit the latter to move axially relatively freely in the sleeve 66. An axial bearing 78 is formed in the body of the cylinder 28 to slidably receive an axial extension 79 formed on the upper end of the ram 75 and engageable with the lower end of an axial extension 80 carried by the piston 48 and projecting downwardly through the bearing 78.

Operation

A suitable dolly 12 is connected to the lower arm of the yoke 10, and in placing the apparatus in position for operation, the operator will manually push the cylinder 28 and ironing plate 68 upwardly until the wall 37 (Figure 4) contacts with the lower end of the tube 24. Before air is turned into the hose 22, the cylinder 28 may be freely pushed upwardly in the manner and for the purpose stated. When the apparatus has been placed in proper position relative to the work, the cylinder 28 may be moved downwardly to engage the flange 69 of the ironing plate 68 with the surface of the metal on which work is to be performed. This engagement of the ironing plate with the work will take place with the flange 29 spaced above the flange 19, and accordingly there will be no positive engagement

between the cylinder 28 and the tool holder 15 through which endwise movement of the cylinder 28 is prevented.

With the apparatus thus placed in position relative to the work, air will be turned into the hose 22 and will flow through passage 25 into the chamber 38. The air will also flow through passages 40 into grooves 41 and 42 and thence through passage or passages 43 into the groove 44. It will be apparent that the pressure in the chamber 38 will exert a downward force on the wall 37, and this force is communicated through the cap 32 to the cylinder 28 to urge the latter downwardly and thus maintain the ironing plate 68 in engagement with the work. Obviously this engagement is maintained solely by the elastic air pressure and not through any positive fixing or clamping of the cylinder 28 relative to the tool holder 15. This is an important feature of the present apparatus.

Assuming that the piston 48 is initially in the position shown in Figure 4, the groove 44 will communicate with the passages 52 and 53 to supply compressed air to the cylinder 28 beneath the piston 48. At the same time, the passages 50 will be out of communication with the groove 44 while the passages 57 will be open to the space above the piston 48 to exhaust such space to the atmosphere. Under such conditions, the piston 48 will be moved upwardly by the air pressure therebeneath.

As the piston 48 moves upwardly, the passages 52 will move out of communication with the groove 44 to cut off the supply of air pressure to the bottom of the cylinder 28 beneath the piston 48. At approximately the same time, the piston 48 will close the exhaust ports 57, after which the space beneath the piston 48 will be exhausted to the atmosphere through ports 61, thus releasing the force tending to move the piston 48 upwardly. At approximately the same time the exhaust ports 61 are opened the passages 50 will move into communication with the groove 44, thus admitting air pressure into the space above the piston 48. Inasmuch as the inertia of the piston 48 will carry it beyond the point at which initial full communication is established between the passages 50 and groove 44, this groove is made substantially wider than the diameters of the passages 50, as shown in Figure 4.

Upon the connection of the space above the piston 48 with the source of pressure in the manner stated, the piston 48 will start to move downwardly. During such downward movement, the passages 50 will move out of communication with the groove 44; the exhaust passages 57 will be uncovered; and the exhaust passages 61 will be covered, the latter operation occurring before the piston 48 reaches the lower end of its stroke. The inertia of the piston 48 will carry it to its lower limit of movement and since the end of the cylinder 28 beneath the piston 48 will be momentarily closed both to the exhaust ports 61 and to the intake ports 52 for a limited period, the pocketing of air in the cylinder 28 beneath the piston 48 will somewhat cushion the movement of the piston toward its lower limit of movement. Just prior to the point at which such limit of movement is reached, the axial extension 80 of the piston will be impacted against the axial extension 79 of the ram 75 to drive the latter downwardly against the work to flatten the latter to remove dents and other irregularities.

When the piston 48 nearly reaches its lower

limit of movement, air pressure will again be supplied to the space beneath the piston to move it upwardly. The reciprocation of the piston thus automatically continues so long as air is supplied through the hose 22, and the ram 75 will be constantly successively impacted against the work to flatten the irregularities therein.

At each upward movement of the piston 48, the upper end of such piston will be carried by its own inertia into engagement with the wall 37, thus causing a relatively light upward impact to be delivered to the cylinder 28 to relieve pressure on the ironing plate 68 against the work. Immediately, however, such upward impact is released the air pressure acting downwardly on the wall 37 reimposes the endwise elastic pressure tending to force the ironing plate 68 downwardly. Thus when reciprocatory pressures are imposed on the ironing plate 68 the rounded 20 flange 69 tends to flatten out irregularities in the work. In this connection, it is pointed out that the pressure head assembly in Figure 4 is moved around relative to the work, and accordingly the ironing plate travels over the work to 25 assist in the smoothing operation. Movement of the ironing plate is facilitated by the fact that pressure of the plate against the work is relieved at each upper limit of movement of the piston 48 in the manner stated. Attention is also invited to the fact that the ram is carried by elements of the apparatus which are cushioned relative to the tool holder, and in practice, therefore, it has been found that the ram has a tendency to gently machine the work surface rather than 30 hammer it.

As previously stated, the pressure in the chamber 38 acting on the upper surface of the wall 37 tends to hold the cylinder 28 in its lowermost position with the ironing plate 68 in engagement 40 with the work. When the piston 48 is moving upwardly, air pressure in the bottom of the cylinder 28 beneath the piston 48 also acts downwardly on the upwardly facing surfaces of the interior of the cylinder. This force is thus added to the force 45 acting downwardly on the wall 37. The additional downward force is released during upward movement of the piston 48 when the exhaust ports 61 are opened, and the force acting downwardly on the wall 37 is at least partly counterbalanced 50 during downward movement of the piston 48 by reason of the fact that the pressure acting downwardly on the piston 48 also acts upwardly against the bottom surface of the wall 37. The downward forces on the upper surface of the wall 37, 55 however, are not completely counterbalanced since there is a relatively constant pressure in the chamber 38 which exceeds the pressure beneath the wall 37 due to the expansion of the space above the piston 48 during downward movement thereof.

Therefore, there is always present an elastic fluid pressure acting downwardly on the cylinder 28 and ironing plate 68. This pressure is greater during upward movement of the piston 60 48 than during downward movement for the reasons explained, but the net downward movement is always sufficient to elastically hold the ironing plate in contact with the work. However, the lighter downward pressure on the plate 68 during 65 downward movement of the piston 48 permits the ironing plate to move slightly during such periods by the application of forces thereto laterally of the axis of the cylinder 28. Moreover, as previously stated, the light impacting of the piston 70 75 48 against the bottom of the wall 37 when the

piston moves upwardly relieves pressure of the ironing plate from the work, thus permitting the assembly to be moved over the work during such periods.

We claim:

1. A sheet metal straightening apparatus comprising a cylindrical support having a closed end, a cylinder mounted in said support and projecting from the other end thereof and axially movable relative to said support, a work-engaging member carried by the projecting end of said cylinder, an air motor carried by said cylinder therewithin and including a reciprocating piston, a ram engageable with said piston and projecting from said cylinder within said work-engaging member to contact with the work, an air hose connected to said support and having an axial tube projecting into said support, said cylinder having an opening fitting said tube to supply air to the interior of said cylinder in any axially moved position thereof, said piston and said cylinder having ports and passages to supply air pressure alternately against opposite ends of said piston to reciprocate it, said cylinder having a surface subject to pressure in said tube whereby, during operation of said motor, said cylinder will be urged toward the work to maintain said work-engaging member in contact therewith.

2. Apparatus constructed in accordance with claim 1 wherein said work-engaging member is in the form of an ironing plate having an annular rib of curved cross-sectional shape engageable with the work to effect an ironing action thereon during operation of said motor.

3. A sheet metal straightening apparatus comprising a cylindrical support having a closed end, a cylinder mounted in said support and projecting from the other end thereof and axially movable relative to said support, a work-engaging member carried by the projecting end of said cylinder, an air motor carried by said cylinder therewithin and including a reciprocating piston, a ram engageable with said piston and projecting from said cylinder within said work-engaging member to contact with the work, an air hose connected to said support and having an axial tube projecting into said support, said cylinder having an opening fitting said tube to supply air to the interior of said cylinder in any axially moved position thereof, said piston and said cylinder having ports and passages to supply air pressure alternately against opposite ends of said piston to reciprocate it, said cylinder having a surface subject to pressure in said tube whereby, during operation of said motor, said cylinder will be urged toward the work to maintain said work-engaging member in contact therewith, a substantially U-shaped arm having one end connected to said support, and a work-engaging element carried by the other end of said arm and engaging the side of the work opposite said work-engaging member.

4. A sheet metal straightening apparatus comprising a cylindrical support having a closed end and an open end, a cylinder mounted in said support and projecting through the open end thereof, said cylinder being axially movable in said support and having a portion engageable therewith to limit movement of said cylinder from the open end of said support, a piston mounted to reciprocate in said cylinder, a cap carried by said cylinder within said support and having an axial chamber, a tubular projection carried by the closed end of said support and extending into said axial chamber, a pressure air line commu-

nicating with said axial chamber through said tubular projection, said cap, said cylinder and said piston having ports and passages for alternately supplying air pressure to the interior of said cylinder at opposite ends of said piston to reciprocate the latter, a work-engaging member carried by the projecting end of said cylinder, said axial chamber having one wall thereof subject to pressure in said chamber to urge said cylinder from said support to maintain said work-engaging member in engagement with the work, and a ram mounted in the projecting end of said cylinder and engageable with said piston and with the work to perform a smoothing operation on the latter.

5. Apparatus constructed in accordance with claim 4 wherein said work-engaging member comprises an ironing plate through which said ram projects, and provided with a depending flange of curved cross-section surrounding said ram.

6. A sheet metal straightening apparatus comprising a cylindrical support having a closed end and an open end, a cylinder mounted in said support and projecting through the open end thereof, said cylinder being axially movable in said support and having a portion engageable therewith to limit movement of said cylinder from the open end of said support, a piston mounted to reciprocate in said cylinder, a cap carried by said cylinder within said support and having an axial chamber, a tubular projection carried by the closed end of said support and extending into said axial chamber, a pressure air line communicating with said axial chamber through said tubular projection, said cap, said cylinder and said piston having ports and passages for alternately supplying air pressure to the interior of said cylinder at opposite ends of said piston to reciprocate the latter, a work-engaging member carried by the projecting end of said cylinder, said axial chamber having one wall thereof subject to pressure in said chamber to urge said cylinder from said support to maintain said work-engaging member in engagement with the work, a ram mounted in the projecting end of said cylinder and engageable with said piston and with the work to perform a smoothing operation on the latter, an arm connected at one end to said support and having its other end terminating at the side of the work opposite said ram, and a work-engaging dolly carried by the last named end of said arm.

7. A sheet metal straightening apparatus comprising a support having a cylindrical bore and provided with a closed end, a cylinder axially movable in said support and projecting from the other end thereof, a work-engaging member carried by the projecting end of said cylinder, an air motor mounted within said cylinder and including a reciprocating piston, a ram engageable with said piston and projecting from said cylinder within said work-engaging member to contact with the work, a chamber in the upper end of said cylinder of substantially smaller diameter than said bore, and having a pressure surface facing away from said other end of said support, a source of air under pressure, and means for supplying air from said source to said chamber and including conduit means extending through the closed end of the support and having a sealed connection with said chamber, said piston and said cylinder having ports and passages to supply air from said chamber alternately against opposite ends of said piston to reciprocate it, said surface being subjected to pressure in said source whereby said

cylinder will be urged toward the work to maintain said work-engaging member in contact therewith.

8. A sheet metal straightening apparatus comprising a support having a cylindrical bore and having a closed end, a cylinder axially movable in said bore and projecting from the other end of said support, a work-engaging member carried by the projecting end of said cylinder, said cylinder having an axial bore, a reciprocating piston in such bore, a ram engageable with said piston and projecting from said cylinder within said work-engaging member to contact with the work, a cap carried by said cylinder and having a hollow axial projection extending into the axial bore of said cylinder and forming a pressure chamber having a pressure surface facing toward the first-named end of said support, a source of air under pressure, and means for supplying air from said source to said chamber and including conduit means extending through the closed end of the support and having a sealed connection with

10

said chamber, said piston and cylinder having ports and passages to supply air from said chamber alternately against opposite ends of said piston to reciprocate it, said surface being subject to the pressure supplied thereto by said air supply means to urge said cylinder toward the work to maintain said work engaging member in contact therewith.
